(57) **CLAIM**

The ornamental design for a fastener head, as shown and described.

DESCRIPTION

FIG. 1 is a top perspective view of the fastener head embodying the new design;

FIG. 2 is an enlarged top perspective view thereof taken from indication circle 2 of FIG. 1;

FIG. 3 is a top perspective view of FIG. 2;

FIG. 4 is a right side view of the fastener head, the left side being a mirror image thereof;

FIG. 5 is a front view of the fastener head, the rear view being a mirror image thereof;

FIG. 6 is an enlarged side view of the fastener head taken from indication box 6 of FIG. 4;

FIG. 7 is an enlarged side view of the fastener head taken from indication box 7 of FIG. 5;

FIG. 8 is an enlarged top view of the fastener head; and,

FIG. 9 is a cross section view of the fastener head taken from line 9-9 of FIG. 8.

The broken lines rendered in the drawings illustrate the environment of the claimed design and forms no part thereof. The broken lines immediately adjacent the solid line portions of the design define the bounds of the claim and form no part thereof.
